UNITED STATES PATENT OFFICE

2,555,107

DRINKING DOLL WITH CONTROLLED
DISCHARGE OF THE LIQUID

Herbert R. Beebe, New York, N. Y., assignor to
American Character Doll Company, New York,
N. Y., a firm

Application May 20, 1949, Serial No. 94,309

5 Claims. (Cl. 46—141)

1

This invention relates to a drinking doll having controlled discharge of the liquid.

Drinking dolls have been constructed with a receptacle for receiving liquid fed through the mouth opening and with a small opening leading from the reservoir and opening through the body of the doll for discharge of the liquid. This construction has the disadvantage that the liquid flows from the doll as soon as the same is received in the receptacle. The present invention overcomes the aforesaid objection and disadvantage incident to the present type of drinking dolls by providing a discharge passageway which is controlled by the movement of one of the limbs of the doll and by which the liquid may be discharged as desired or stored within the body of the doll.

Another object of the invention is the provision of a doll of said character in which one of the limbs thereof is provided with a valve stem having a valve opening adapted to register with the discharge opening when the limb member is disposed in one position for permitting of the discharge of liquid from said receptacle, and the stem being moved to close said discharge outlet when the limb member is disposed in another position.

Still another object of the invention is the provision of a drinking doll in which the stem connected with the limb member extends into the liquid receiving receptacle located within the body of the doll and which stem is movable to and from covering relation with the discharge outlet.

Still another object of the invention is the provision of means tensioning the inner end of the stem against the inner face of the receptacle to provide a liquid tight swivel connection.

With the foregoing and other objects in view, reference is now made to the following specification and accompanying drawings in which the preferred embodiment of the invention is illustrated.

In the drawings:

Fig. 1 is a longitudinal medial sectional view through a doll constructed in accordance with the invention.

Fig. 2 is an enlarged fragmentary sectional view taken approximately on line 2—2 of Fig. 1.

Fig. 3 is a similar view taken approximately on line 3—3 of Fig. 2.

Fig. 4 is a horizontal sectional view taken approximately on line 4—4 of Fig. 3.

Referring to the drawings by characters of reference, the drinking doll includes a receptacle 10 which is located within the body 11 of the doll and

2

is adapted to receive liquid fed to the doll through the mouth opening 12 thereof. The liquid is conveyed to the receptacle 10 through a conduit 13 which is connected with the head at the mouth opening and extends downwardly through the upper end of the body 11 with the lower end of the conduit protruding through the restricted lower end of a conical shaped member 14 connected at its upper end with the receptacle 10 and adapted to prevent leakage of the liquid through the top of the receptacle. The receptacle 10 is provided with a conduit 15 integrally connected with the lower end thereof and connected with the body 11 so as to form a restricted discharge passageway 16 opening through the body 11 adjacent the leg members 17.

In order to control the discharge of the liquid, a valve stem 18 is provided which is formed with a flared rim 19 having a small aperture 20 therethrough and which stem is rotatably mounted in an opening 21 in the lower end of the receptacle 10 with the flared rim 19 disposed in engagement with a frusto-conical shaped seat 22 formed at the inner end of the opening 21. The rim 19 slidably fits the seat 22 with the aperture 20 thereof being adapted to register with a transverse duct 23 opening through the seat and communicating at its outer end with the discharge passageway 16.

The opening 21 is provided in a downwardly and inwardly directed bottom wall portion 24 of the receptacle to thereby dispose the valve stem 18 in downwardly directed angular relation with the longitudinal axis of the receptacle and with the flattened lower end 25 thereof slidably engaging through an elongated slit 26 formed in and extending across the upper inner end of one of the leg members 17.

The leg members 17 are fitted in circular openings 27 in the body 11 of the doll so as to swivelly connect the leg members therewith when the legs are moved from depending or in standing relation to right angular position or in seated relation to thereby rotate the valve stem 18 in the opening 21 to move the aperture 20 to and from registry with the duct 23. The aperture 20 is positioned in the rim 19 so that when the leg 17 is in a depending position the discharge passageway 16 is closed so as to retain the liquid in the receptacle 10 and when the leg is moved to right angular relation with the body, the passageway 16 is opened to permit of the discharge of the liquid from the receptacle.

A coil spring 28 disposed in surrounding relation with the valve stem 18 is tensioned between

metallic washers 23 and 33 positioned against the lower end 24 of the receptacle and against a cross pin 34 projecting through the valve stem 18 for tensioning the flanged rim 19 against the seat 22 so as to provide a leak-proof joint therebetween.

What is claimed is:

1. In a doll, a body having a compartment for containing liquid and having a discharge passageway opening through a wall thereof, a limb member connected with said body for turning movement, a stem connected with said limb member for turning movement thereof with the movement of the limb member, said stem having an opening adapted to register with the discharge passageway when the limb member is disposed in one position for permitting of the discharge of liquid from the compartment, and said stem being moved to dispose said opening out of registry with the discharge passageway when the limb member is disposed in another position.
2. In a doll, a body having a compartment for containing liquid and having a discharge passageway opening through a wall thereof, a limb member connected with said body for turning movement, a stem mounted for rotation in a wall of said compartment and connected with said limb member for movement therewith, said stem having an opening adapted to register with the discharge passageway when the limb member is disposed in one position for permitting of the discharge of liquid from the compartment, and said stem being moved to dispose said opening out of registry with the discharge passageway when the limb member is disposed in another position.
3. In a doll, a body having a compartment for containing liquid, said compartment having an inclined apertured wall provided with a discharge outlet opening therethrough, a limb member connected with said body for turning movement, a valve element mounted for rotation in the aperture in said inclined wall and having a valve stem disposed in downwardly directed inclined relation and connected with said limb member for turning movement therewith, and said valve element having an opening adapted to register with the discharge outlet when the limb member is disposed in one position for permitting of the discharge of liquid from the compartment, and said valve element being moved to dispose said opening out of registry with the discharge outlet when the limb member is disposed in another position.
4. In a doll, a body having a compartment for containing liquid, said compartment having an

inclined apertured wall provided with a discharge outlet opening therethrough, a limb member connected with said body for turning movement, a valve element mounted for rotation in the aperture in said inclined wall and having a valve stem disposed in downwardly directed inclined relation and connected with said limb member for turning movement therewith, said valve element having an opening adapted to register with the discharge outlet when the limb member is disposed in one position for permitting of the discharge of liquid from the compartment and said valve element being moved to dispose said opening out of registry with the discharge outlet when the limb member is disposed in another position, and a spring surrounding said valve stem and engaging against the inclined wall of said compartment for tensioning the valve element for providing a liquid-tight connection in the aperture in said inclined wall.

5. In a doll, a body casing, a liquid-receiving receptacle located within said casing and having an inclined apertured wall provided with a discharge outlet opening through a wall of said casing, a limb member connected with said body casing for turning movement, a valve element mounted for rotation in the aperture in said inclined wall and having a downwardly directed inclined stem engaging said limb member for turning movement therewith, said valve element having an aperture adapted to register with said discharge outlet when the limb member is disposed in one position for permitting of the discharge of liquid from the receptacle and said valve element being moved to dispose said aperture out of registry with the discharge outlet to prevent discharge of the liquid when the limb member is disposed in another position, and spring means engaging said valve stem for tensioning said valve element in the aperture in said inclined wall.
